UNITED STATES PATENT OFFICE.

THOMAS E. CHERRY, OF BOSTON, MASSACHUSETTS.

ADDING MACHINE.

Application filed March 16, 1922. Serial No. 544,085.

To all whom it may concern:

Be it known that I, THOMAS E. CHERRY, a citizen of the United States, residing at Boston, in the county of Suffolk and State of Massachusetts, have invented new and useful Improvements in Adding Machines, of which the following is a specification.

This invention relates to an adding machine which includes a carriage carrying a rotary platen, and adapted to be automatically reciprocated endwise, as in a so-called shuttle machine, when such reciprocation is desired, the type of machine to which the invention relates being well known under the name of the Wales adding machine.

A machine of this type includes well known mechanism whereby the machine may be converted from an adding to a non-adding machine, and vice versa. In the Wales machine this conversion is effected by the simple operation of shifting and changing the height of a converting cross shaft which is adapted, when shifted downwardly, to render the adding mechanism operative, and, when shifted upwardly, to render the adding mechanism inoperative, the machine being operable in one case to print and add, and in the other case to print without adding. Heretofore, the said converting shaft has been shifted manually.

My invention has for its chief object to provide means for causing the machine to add when the platen is at one end of its reciprocating movement, and is in position to permit the printing of figures on the edge portion of the record sheet, at the right hand of the operator, and for rendering the machine incapable of adding when the platen is at the opposite end of its reciprocating movement, and in position to permit the printing of figures on the portion of the sheet at the left hand of the operator.

The invention is embodied in the improvements hereinafter described and claimed.

Of the accompanying drawings forming a part of this specification,—

Figure 1 is a side elevation of an adding machine embodying the invention, the typing mechanism, excepting the platen, being omitted, and the converting shaft shown in non-adding position.

Figure 1^a is a view similar to a portion of Figure 1, showing the converting shaft in adding position.

Figures 2, 3 and 4 are fragmentary ele-

vations, showing details of portions of the mechanism in which the invention is embodied.

Figure 5 is a fragmentary perspective view, showing certain details of the carriage-reciprocating mechanism.

Figure 6 is a top plan view, showing the rear end portion of the machine reversed from the position shown by Figure 1, various parts shown by Figure 1 being omitted.

Figure 7 is an end elevation of the cam cylinder, hereinafter described, and certain parts cooperating therewith.

Figure 8 shows in perspective the mechanism shown by Figure 6.

Figure 9 is an end elevation of the structure shown in plan by Figure 6.

The same reference characters indicate the same parts in all of the figures.

To illustrate my invention I have shown certain elements of the well known Wales adding machine, and have designated said elements by reference letters.

a represents the carriage in which the impression roll or platen *b* is journaled, said carriage and platen being movable longitudinally and guided by the usual guiding members *c*, *c*, fixed to the frame *d*. *e* represents the rock-shaft which is rocked in bearings in the frame by the alternate action of a hand lever *f* movable by the operator to turn the rock-shaft in one direction, and a spring *g*, secured at one end to the frame, and at the other end to an arm *h* on the rock-shaft, the spring turning the rock-shaft in the opposite direction when the lever is released. The platen *b* is rotated step by step by the usual mechanism, which includes a push-rod *j* having an end face *j'* (Figure 1), and a transverse bar or carriage-rod *k*, supported at opposite ends by two arms *l*, only one of which is shown, said arms being pivoted at *o*, to the end portions of the carriage. The end face *j'* normally contacts with the carriage-rod *k*. One of the arms *l* is the longer arm of a bell-crank lever, to the shorter arm *l'* of which is pivoted an arm *l''*, carrying the usual pawl *t*, cooperating with a ratchet *u* on the platen to rotate the latter step by step.

The carriage-rod *k* is moved laterally in one direction to cause a partial rotation of the platen by an outward movement of the lever *f* from the position shown by Figure 1. The lever *f* is connected with the push-

rod *j* in such manner that an outward movement of the lever causes an inward movement of the push-rod in the direction of arrow *w* (Figure 1), this movement causing the end face *j'* of the push-rod to move the carriage-rod *k* in the same direction, and thus impart a platen-rotating movement to the pawl *t*. When the lever *f* is returned by the spring *g* to the position shown by Figure 1, the push-rod *j* is moved outward, and allows the carriage-rod *k* to be moved by gravity in the same direction, the pawl slipping back on the ratchet. The connections between the push-rod *j* and the lever *f* include a rocker-arm fulcrumed at *S* on the frame *d*. The rocker-arm is pivoted at one side of its fulcrum by a pin *s'*, to the push-rod, and at the opposite side of its fulcrum by a pin *s*², to one end of a link *f'*, the opposite end of which is pivoted by a pin *j'* to an arm *e*² in the rock-shaft *e*.

The carriage *a* has the usual rod *p*, which is fixed at its ends to the carriage and is parallel with the platen *b*.

My application filed August 24, 1921, Serial No. 494,998, describes and claims certain mechanism constituting an attachment which is applicable to a machine comprising the elements above described, and constituting a simple means for automatically reciprocating the carriage and platen endwise, as in so-called "shuttle" adding machines; for varying the length of the stroke or reciprocating movement of the carriage or platen, so that the paper constituting the record sheet or strip may be moved edgewise in some cases farther than in others; for conveniently disconnecting the carriage from the automatic mechanism which reciprocates it, so that the carriage and platen may be moved endwise by hand; for automatically disconnecting the platen from the mechanism which rotates it, so that the platen will be non-rotating during a predetermined period, and will be rotated step-by-step during another period; and for manually displacing the usual member which normally prevents movement of the carriage from left to right, to permit such movement when it is desired.

To facilitate an understanding of the present invention, I will now describe the mechanism in which the invention of the above-mentioned application is embodied.

12 represents a base plate or base extension which is attached by bolts 13 to the usual base *d'* supporting the frame *d*, said bolts being substituted, in the type of machine here shown, for two of the usual supporting feet *d*², the feet at the rear portion of the base being removed and replaced by the bolts 13. Fixed to the base extension 12 is an upwardly projecting frame 14, having bearings for a shaft 15, extending parallel with the platen. Mounted to turn loose-

ly on the shaft 15 is a carriage-reciprocating cam, comprising a cylinder 16, having a continuous cam groove 17, and hereinafter referred to as the carriage cam. To one end of the carriage cam is fixed a ratchet disk 18', having diametrically opposite notches 18, engaged by pawls 19, which are pivoted to a cam disk 20. The disk 20 is fixed to a pinion 26, which is rigid on the shaft 15. The carriage cam 16 is intermittently rotated by mechanism which is differently organized from that shown for the same purpose in my former application, and includes a gear 22, the shaft of which is journaled in a fixed standard 23 on the base plate 12, an arm 24 fixed to the gear 22, a rod 25, connecting the arm 24 with an arm *e*' fixed to the rock-shaft *e*, the above-mentioned gear 26 fixed to the shaft 15, and an idle connecting gear 27 interposed between the gears 22 and 26. When the lever *f* is moved forward and backward by the operator, the gears 22, 27 and 26, and the cam disk 20 are rocked or rotated, and the disk and the pawls 19 carried thereby, when moved in the direction indicated by the arrow in Figure 7, engage the notches 18, and partially rotate the carriage cam in the same direction.

When the pawls 19 rotate the carriage cam, the cam is prevented from rotating too far by a spring-pressed detent 30, engaging either of two recesses 31 in one end of the carriage cam, said recesses and detent being formed to positively prevent forward rotation of the cam 16, beyond the determined point. The detent is movable in a fixed guide, and has a pin 30^a, which is acted on by a cam 20^a on the disk 20, when the disk is turned in one direction to disengage the detent from the recess 31 with which it is engaged, thus unlocking the carriage cam.

Movement is communicated from the carriage cam to the carriage by a lever designated as a whole by the reference numeral 33. Said lever has a fulcrum stud 34, journaled in a fixed bearing 35, and has at one end a trundle-roll 36, entering the groove 17 of the carriage cam, and at its opposite end a stud 42, adapted to engage a slotted arm 45, secured as shown by Figure 5, to the carriage-rod *p*.

The means for preventing rotation of the platen during a predetermined period, and causing it to rotate step-by-step during another period, may be as shown in my above-mentioned application, said means including an arcuate cam rib or projection on the carriage cam, a roller in the path of said cam rib and attached to an arm projecting outwardly from a rock-shaft 60, carried in a vertical bearing 61, fixed to the frame 14. At the upper end of the shaft 60 is a disk 62, having mounted thereon a roller 63, adapted to engage the carriage-rod *k* and

move the same sidewise to a rear position, thus rendering it inoperative, or preventing it from imparting rotation to the platen.

The above-described carriage-reciprocating mechanism may be installed in a machine not provided with means for automatically reciprocating the carriage and platen, in the manner described in my former application.

10 In Figures 1 and 1^a I show the usual converting shaft *s*, through the shifting of which the machine is converted from an adding to a non-adding machine, and vice versa, said shaft and the mechanism (not 15 shown) with which it cooperates being well known elements of the Wales adding machine. Since my invention is embodied in the mechanism hereinafter described, for shifting the shaft *s*, I do not deem it necessary to show and describe the elements with 20 which said shaft cooperates.

The converting shaft *s* is movable vertically in guides *d*², in the frame *d*, and is provided with trunnions *t* from which depend rods or struts *u*. When the shaft *s* is lowered, as shown by Figure 1^a, the machine is operable to print and add, and when the shaft is raised, as shown by Figure 1, the machine is operable to print without 30 adding.

The shaft *s* is supported in its non-adding position as usual, by the engagement of the lower end of the struts *u* with the notched studs *v*, and by the engagement with the trunnions *t* of oscillatory hooked latch arms *w*, pivoted to a cross shaft *x* journaled in the frame *d*. Heretofore the shifting of the shaft *s* from the non-adding position to the adding position has been performed by manually displacing the latch arms *w* and the struts *u* from the positions shown by Figure 1, to those shown by Figure 1^a. To raise the shaft *s* to its non-adding position, it has been necessary to depress a non-adding key (not shown) located in the top of the machine, said key being connected to the shaft *x* in such manner that when the key is depressed, a clockwise partial rotation of the latch arms *w* is caused, placing the arms in the position shown in Figure 1. To lower the shaft *s* to the adding position, it has been necessary to depress an adding key (not shown), located in the top of the machine, and similarly connected to the shaft *x*, but arranged in such a manner that when the said key is depressed, it will cause an anti-clockwise movement of the arms *w*.

The mechanism in which the present invention is embodied, is organized to cause the machine to add when the platen is at one end of its reciprocating movement, and is in position to permit the printing of figures on the edge portion of the record sheet, at the right hand of the operator, and to render the machine incapable of adding when the

platen is at the opposite end of its reciprocating movement, and in position to permit the printing of figures on the portion of the sheet at the left hand of the operator. To accomplish this result the carriage cam 16 is 70 provided at one end with a segmental cam 67, arranged to contact with, and displace a trundle-roll 68, constituting an element of mechanism for swinging the latch-arm *w* to either of the positions shown by Figures 1 and 1^a. Said mechanism, as here shown, includes a movable bearing piece 69 at the upper side of the base plate 12, carrying the roll 68, a slide 70, at the lower side of the base plate, and rigidly connected with the bearing piece by a rivet 71, which is movable in a slot (not shown) in the base plate, the bearing piece 69 and slide 70 being guided by studs 72 and 73, fixed to the base plate and passing through slots 72^a and 73^a, 80 a rocker arm 74 pivoted at 75 to the base plate, a slide 76, pivoted to one end of the rocker-arm, and guided at the under side of the base plate by a stud 77, fixed to the base plate, and entering a slot 78 in the 90 slide 76.

The displacement of the roller 68 by the cam 67 causes the slides 70 and 76 to move endwise in opposite directions. The movement of the slide 76 swings a vertical lever 79, included in said mechanism, through a spring 80, attached at one end to the slide, and at its opposite end to a stud 80^a, adjustably connected with the lower end of the lever 79. Said lever is pivoted at 81 to a fixed ear 82, on the frame *d*, and its upper end is connected by a link 83 with the swinging end of the latch-arm *w*. The function of the spring 80 is to press the roller 68 toward the axis of the carriage cam 16, and hold it in the path of the cam 67. I provide means, however, for rendering the spring inoperative to perform this function, said means being embodied in a rotatable member 84, journaled in the lower end of the upright lever 79, and carrying the pin 80^a, with which the spring is connected, said member having a knurled knob 85 by which it may be turned to locate the pin 80^a, either in the position shown by Figures 2, 3 and 8, to exert tension on the spring 80, and render it operative, or in the position shown by Figure 4, to slacken the spring and render it inoperative. A stop pin 86, on the lever 79, cooperates with a stop finger 87 on the member 84, in maintaining tension on the spring.

It will now be seen that when the spring 80 is operative, contact of the cam 67 with the roll 68 will cause the latch arm *w* to swing forward to the position shown by Figure 1, and hold up the converting shaft *s* in the non-adding position, and that when the cam 67 recedes from the roll 68, the spring 80 moves the latch arm to permit the

shaft s to drop to its adding position. When the spring 80 is made inoperative, as indicated by Figure 4, the latch arm remains in the position shown by Figure 1^a.

5 I claim:

1. An adding machine comprising in combination a platen carriage, means including a step-by-step rotated carriage cam, and a lever cooperating therewith to reciprocate the carriage, a shiftable converting shaft adapted to occupy either an adding or a non-adding position, a latch detachably engageable with the converting shaft to support the latter, and automatic means actuated by the 10 rotation of the carriage cam for disengaging the latch from the converting shaft.
2. An adding machine comprising in combination a platen carriage, means including a step-by-step rotated carriage cam, and a lever cooperating therewith to reciprocate the carriage, a shiftable converting shaft adapted to occupy either an adding or a non-adding position, a latch detachably engageable with the converting shaft to support the latter, automatic means actuated by the 15 rotation of the carriage cam for disengaging the latch from the converting shaft, and manually operable means for rendering said automatic means inoperative.
3. An adding machine comprising in combination a platen carriage, means including a step-by-step rotated carriage cam, and a lever cooperating therewith to reciprocate the carriage, a shiftable converting shaft adapted to occupy either an adding or a non-adding position, a latch arm adapted to maintain said shaft in its non-adding position, and automatic means actuated by the 20 rotation of the carriage cam for moving said latch arm to and from its operative position.
4. An adding machine comprising in combination a platen carriage, means including a step-by-step rotated carriage cam, and a lever cooperating therewith to reciprocate the carriage, a shiftable converting shaft adapted to occupy either an adding or a non-adding position, a latch arm adapted to maintain said shaft in its non-adding position, a segmental cam on the carriage cam, 25 and mechanism intermediate of the segmental cam and the latch arm for imparting movement from the cam to the latch arm to shift the latter to and from its operative position.
5. An adding machine comprising in combination a platen carriage, means including a step-by-step rotated carriage cam, and a lever cooperating therewith to reciprocate the carriage, a shiftable converting shaft adapted to occupy either an adding or a non-adding position, a latch arm adapted 30

to maintain said shaft in its non-adding position, a segmental cam on the carriage cam, mechanism intermediate of the segmental cam and the latch arm for imparting movement from the cam to the latch arm to shift the latter to and from its operative position, and manually operable means for rendering said intermediate mechanism inoperative. 65

6. An adding machine comprising in combination a platen carriage, means including a step-by-step rotated carriage cam, and a lever cooperating therewith to reciprocate the carriage, a shiftable converting shaft adapted to occupy either an adding or a non-adding position, a latch arm adapted to maintain said shaft in its non-adding position, a segmental cam on the carriage cam, mechanism intermediate of the segmental cam and the latch arm for imparting movement from the cam to the latch arm to shift the latter to and from its operative position, 70 said mechanism including a trundle-roll, and a spring whereby said roll is normally pressed toward the axis of the carriage cam and against the segmental cam. 75

7. An adding machine comprising in combination a platen, carriage, means including a step-by-step rotated carriage cam, and a lever cooperating therewith to reciprocate the carriage, a shiftable converting shaft adapted to occupy either an adding or a non-adding position, a latch arm adapted to maintain said shaft in its non-adding position, a segmental cam on the carriage cam, mechanism intermediate of the segmental cam and the latch arm for imparting movement from the cam to the latch arm to shift the latter to and from its operative position, 80 said mechanism including a trundle-roll, and a spring whereby said roll is normally pressed toward the axis of the carriage cam and against the segmental cam, means being provided for slackening the spring and rendering said mechanism inoperative. 85

8. An adding machine comprising in combination, a rotary platen; a movable carriage therefor; normally operable mechanism including a hand lever for rotating the platen step-by-step, and carriage-reciprocating mechanism including a carriage cam, a lever oscillated by said cam, a lever-engaging member on the carriage, a gear coaxial with the cam and independently rotatable, one-way rotating connections between the 90 coaxial gear and the cam, and means for reversely rotating the coaxial gear including a gear reversely rotated by the hand lever, and an intermediate gear. 95

In testimony whereof I have affixed my 100 signature.

THOMAS E. CHERRY.
